UNITED STATES PATENT OFFICE.

WILLIAM L. McGRATH, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,396,518.

Specification of Letters Patent. Patented Nov. 8, 1921.

Application filed November 13, 1919. Serial No. 337,725.

To all whom it may concern:

Be it known that I, WILLIAM L. McGRATH, a citizen of the United States, residing at Elmira, in the county of Chemung 5 and State of New York, have invented certain new and useful Improvements in Engine-Starters, of which the following is a specification.

My invention pertains to engine starters 10 and relates more particularly to the drive or transmission portion thereof interposed between the prime mover such as an electric motor and a member of the engine to be started, such as the fly wheel thereof. 15 The object of my invention is to provide a simple, efficient and reliable drive of a type characterized by the manual operation of the driving member of the drive for engagement or meshing with the fly wheel, and 20 by the automatic disengagement of such driving member when the engine has started on its own power.

In the drawings Figure 1 is a sectional elevation of a starter system embodying my 25 invention; Fig. 2 an end elevation thereof; Fig. 3 a section on the line 3-3 of Fig. 1; and Fig. 4 a sectional elevation of a modified form of construction.

For the purposes of a clear and definite 30 description I have selected one of many embodiments of my invention, the same being here shown as of the single reduction type in which the drive is direct driven by the motor, although it may be indirectly 35 driven, and may have other modifications, and may partake of other forms without departing from the spirit of my invention.

As shown the starting motor 1 has an 40 extended armature shaft 2 journaled at its outer end in a bearing 3^a provided by the inclosing casing or bracket 3 which is secured to, or supported by, the motor frame. This rotatable or drive shaft 2 is provided intermediate its length with spiral splines 4.

45 The driving member is here in the form of a pinion 5 and is provided with corresponding spiral splines in its central bore to coact with the splines of the shaft, with the result that the pinion is mounted thereon for longitudinal movement thereof and 50 rotary movement therewith after its longitudinal movement has been arrested by contact with the stop nut 6, at which time the pinion is in engagement or mesh with the fly wheel 7. The pinion is provided with an

inwardly extending sleeve or hub portion 8 terminating in a head 9 which is provided on its forward side with the irregular or cam surface 10, adapted to coöperate with the rolls of the shifting fork hereinafter 60 described.

The means for shifting the pinion which are operated by hand or foot as desired, consists of a depressible plunger and lever connections and shifter interposed between 65 it and the pinion head. The shifter consists of a sleeve 11 mounted to slide on a shaft or rod 12 suitably mounted in the casing 3. This sleeve is provided with the fork or bifurcated arms 13 carrying at their 70 lower ends rolls 14 adapted to coöperate with the track or irregular surface 10 of the pinion head. The upper outer corner of this sleeve 11 is shaped to form a recess 15 with a high shoulder or side 16 and a 75 low shoulder or side 17.

The lever connections for shifting the sleeve 11 consist of a bell crank 18 pivoted at 19 at the upper end of the vertical bracket arms 20 rising from the top of the 80 casing 3. The lower or vertical arm of the bell crank enters within the recess 15 and is provided at its lower outer corner with a small finger 21 pivoted thereto at 22. The bell crank is held in its normal position 85 illustrated by a yielding pressure which is here afforded by means of the torsion spring 23 encircling the pivot pin 19 and connected at its ends with an arm 20 and with the bell crank with the result that any 90 movement of such bell crank in an anti-clockwise direction is resisted by the spring.

The upper or horizontal arm of the bell crank is operated by the vertical plunger 24 passing through and guided by suitable 95 supports such as the floor board 25 of an automobile, and by a horizontal plate 26 therebelow. This plunger is normally held in the position shown by the coiled spring 27, and such plunger carries at its lower 100 end a lateral arm 28 which is provided at its outer end with an adjustable screw 29 adapted to contact and operate the bell crank.

The plunger 24 is in vertical alinement 105 with a movable element of a switch 30, here shown as attached to the motor frame and adapted to control the electrical circuit of the motor.

Describing a cycle of operation and begin- 110

ning with the parts in their normal position shown in Fig. 1, depression of the plunger 24 by hand or foot will oscillate the bell crank to the first dotted line position, with the result that the finger 21 will engage the shoulder 17 and then move the sleeve longitudinally along its supporting shaft 12. The fork, or arms 13 will thereupon shift the pinion to the right into engagement with the fly wheel. In this movement the pinion is rotated slightly by reason of the splines. The construction and arrangement may be such that full mesh of the pinion may be established by hand or only a partial mesh, after which the starting motor when operated will establish full mesh and subsequent rotation of the pinion and the fly wheel. When the plunger has substantially reached its lower limit of depression it will contact and operate the switch 30, whereupon the motor will be operated and the drive shaft 2 rotated, with the result that the pinion 5 if not in full mesh is automatically brought into full mesh and the fly wheel rotated. When the engine has started on its own power the pinion will be automatically demeshed in the well-known manner. In this operation the torsion spring 23 will return the bell crank and the sleeve 11 to normal position, the pivoted finger 21 riding over the outer corner of such sleeve and then taking its position with the lower end of the bell crank arm within the recess 15. This finger is provided to enable the reengagement of the bell crank with such recess after the pinion has been demeshed through the starting of the engine before the manual release of the bell crank. The first set of dotted lines represents the position of the sleeve 11 at the time of partial mesh, and the second or outermost set to the right representing the position of such sleeve when in full mesh.

In the event that the meshing operation is not perfect, as when the teeth of the pinion and fly wheel abut end to end, the movement of the plunger will thereby be stopped before contacting the starting switch 30. On releasing the plunger the torsion spring on the bell crank will withdraw the pinion through the shifting fork, the rolls of the latter contacting the irregular surface 10. Should this contact occur at the bottom of such cam surface as indicated in the drawing, it will prevent the turning of the pinion during retraction and will cause a slight turning of the shaft. Should the contact occur at a point other than the bottom of the irregular surface, it will cause the turning of the pinion and of course the shaft therewith. In either case, the next attempt at starting will then cause a different registration of the teeth and meshing will be accomplished.

In Fig. 4 I have illustrated a modified

form of construction which differs from the one already described in the provision of a yielding driving connection between the driving shaft and the pinion. According to this construction the drive shaft 31 of the motor is a short hollow stub shaft adapted to receive the inner end of the rotatable shaft 32 of the drive. These two shafts are operatively connected by a yielding driving connection which is here a coiled driving spring 33 connected at its opposite ends to the two shafts 31 and 32 by means of the studs 34 and 35, respectively. The pinion 5 is the same in construction and operation as that already described, and is mounted upon the drive shaft 32 in the same manner as the other pinion was mounted upon the drive shaft 2.

The shifter means are manually or pedally operable which for convenience I have herein designated as manual operation, as distinguished from power or from automatic operation.

I claim:

1. An engine starter drive including a rotatable shaft, a driving member mounted thereon for rotary movement therewith and for longitudinal movement thereof to engage a part of the engine to be started, and means adapted to cause such longitudinal movement of the driving member and to retract the same and also to cause a slight rotary movement thereof on its retracting movement away from such engine part. 90

2. An engine starter drive including a rotatable shaft, a driving member mounted thereon for rotary movement therewith and for longitudinal movement thereof to engage a part of the engine to be started, and means adapted to cause such longitudinal movement of the driving member and to retract the same, said means and driving member having elements co-operating with each other on the retracting movement of such member away from such engine part to cause 100 a slight rotary movement thereof. 105

3. An engine starter drive including a rotatable shaft, a driving member mounted thereon for rotary movement therewith and for longitudinal movement thereof to engage a part of the engine to be started, and having a cam face thereon, and manually operated means adapted to cause such longitudinal movement of the driving member and to retract the same such means co-operating with such cam face on the retracting movement thereof away from such engine part to cause a slight rotary movement thereof. 115

4. An engine starter drive including a rotatable shaft, a driving member mounted thereon for rotary movement therewith and for longitudinal movement thereof to engage a part of the engine to be started, and having a cam face thereon, and means adapted 125 to cause such longitudinal movement of the driving member and to retract the same such means co-operating with such cam face on the retracting movement thereof away from such engine part to cause a slight rotary movement thereof. 130

- to cause such longitudinal movement of the driving member, and including a shifter having rolls adapted to coöperate with such cam face on the retracting movement of the 5 driving member whereby the latter is caused to rotate slightly.
5. An engine starter drive including a rotatable shaft, a driving member mounted thereon for rotary movement therewith and 10 for longitudinal movement thereof to engage a part of the engine to be started, and having at one end a sleeve extension terminating in a head provided on its inner side with a cam face, and a shifter adapted when 15 moved in one direction to shift the driving member longitudinally and to engage the cam face on its return movement to cause a slight rotary movement of the driving member.
10. An engine starter drive including a rotatable shaft, a driving member mounted thereon for rotary movement therewith and 15 for longitudinal movement thereof to engage a part of the engine to be started, and means 20 for shifting the driving member comprising a supporting shaft, arranged parallel to the 25 rotatable shaft, a shifter mounted to slide on the supporting shaft and having arms operatively connected with the driving member, and a lever operatively connected with the 30 shifter for shifting it a predetermined distance but adapted to detach itself therefrom for the remainder of the distance, and to reengage therewith when returned to normal position, said shifter being pressed to 35 normal position with a yielding pressure and acting on the driving member to restore it to normal position.
10. An engine starter drive including a rotatable shaft, a driving member mounted thereon for rotary movement therewith and 40 for longitudinal movement thereof to engage a part of the engine to be started, and means 45 for shifting the driving member comprising a supporting shaft, arranged parallel to the 50 rotatable shaft, a shifter mounted to slide on the supporting shaft and having arms operatively connected with the driving member, and a lever operatively connected with the 55 shifter for shifting it a predetermined distance but adapted to detach itself therefrom for the remainder of the distance, and to reengage therewith when returned to normal position, said shifter being pressed to 60 normal position with a yielding pressure and acting on the driving member to restore it to normal position.
10. An engine starter drive including a rotatable shaft, a driving member mounted thereon for rotary movement therewith and 65 for longitudinal movement thereof to engage a part of the engine to be started, and means 70 for shifting the driving member comprising a supporting shaft, arranged parallel to the 75 rotatable shaft, a shifter mounted to slide on the supporting shaft and having arms operatively connected with the driving member, and a lever operatively connected with the 80 shifter for shifting it a predetermined distance but adapted to detach itself therefrom for the remainder of the distance, and to reengage therewith when returned to normal position, said shifter being pressed to 85 normal position with a yielding pressure and acting on the driving member to restore it to normal position.
10. An engine starter drive including a rotatable shaft, a driving member mounted thereon for rotary movement therewith and 90 for longitudinal movement thereof to engage a part of the engine to be started, and means 95 for shifting the driving member comprising a supporting shaft, arranged parallel to the 100 rotatable shaft, a shifter mounted to slide on the supporting shaft and having arms operatively connected with the driving member, and a lever operatively connected with the 105 shifter for shifting it a predetermined distance but adapted to detach itself therefrom for the remainder of the distance, and to reengage therewith when returned to normal position, and a spring acting on the 110 lever to hold the same and the shifter and also the driving member in a normal position.
11. An engine starter drive including a rotatable shaft, a driving member mounted thereon for rotary movement therewith and 115 for longitudinal movement thereof to engage a part of the engine to be started, and means 120 for shifting the driving member comprising a supporting shaft arranged parallel to the 125 rotatable shaft, a shifter mounted to slide on the supporting shaft and having arms operatively connected with the driving member, said shifter having a recess, a lever having one end normally positioned in such recess and bearing against the shifter to hold it in 130 normal position and having a pivoted finger on such end and adapted to coöperate with the recess to move the shifter a predetermined distance and then clear the recess and subsequently return thereunto and a single means for restoring the parts to normal position.
12. An engine starter drive including a rotatable shaft, a driving member mounted thereon for rotary movement therewith and 135 for longitudinal movement thereof to engage a part of the engine to be started, and means 140 for shifting the driving member comprising a supporting shaft arranged parallel to the 145 rotatable shaft, a shifter mounted to slide on the supporting shaft and having arms operatively connected with the driving member and normally bearing thereagainst with a yielding pressure, a bell crank having one arm operatively connected 150

with the shifter, and a manually operated plunger for actuating the bell crank.

13. An engine starter drive including a rotatable shaft, a driving member mounted thereon for longitudinal movement thereof to engage a part of the engine to be started and rotary movement therewith, and means adapted to cause such longitudinal movement of the driving member and to retract the same and also to cause a slight rotary movement thereof on its retracting movement away from the engine part, a driving shaft, and a yielding driving connection between the two shafts.

14. An engine starter drive including a rotatable shaft, a driving member mounted thereon for longitudinal movement thereof to engage a part of the engine to be started and rotary movement therewith, and means adapted to cause such longitudinal movement of the driving member and to retract the same and also to cause a slight rotary movement thereof on its retracting movement away from the engine part, a driving shaft, and a spring drive between the two shafts. 20 25 15

WILLIAM L. McGRATH.

1. *Urticaria* - *Urticaria* is a condition in which the skin becomes red, swollen, and itchy. It is caused by an allergic reaction to certain substances, such as pollen, dust, or food. The symptoms usually appear within a few hours of exposure and can last for several hours or days. Treatment for *urticaria* may include antihistamines, corticosteroids, or other medications to relieve symptoms.
